(57) CLAIM

The ornamental design for a swimming pool wall brace, as shown and described.

DESCRIPTION

FIG. 1 is a perspective view of a swimming pool wall brace showing my new design;

FIG. 2 is a front view thereof;

FIG. 3 is a back view thereof;

FIG. 4 is a top view thereof; and

FIG. 5 is a bottom view thereof;

FIG. 6 is an edge view thereof, as seen from the left edge in FIG. 2; and,

FIG. 7 is an edge view thereof, as seen from the right edge of FIG. 2.

As mounted outside and against a wall of a swimming pool, beneath a gutter of the swimming pool, such a brace is used to brace the wall against outwardly directed forces, which are imparted when the swimming pool is filled with water, and to support the gutter.
